UNITED STATES PATENT OFFICE.

JAK ESENKO, OF MILL CREEK, BRITISH COLUMBIA, CANADA.

EXPANSIBLE SHAFT.

1,171,417.

Specification of Letters Patent. Patented Feb. 15, 1916.

Application filed May 29, 1915. Serial No. 31,229.

To all whom it may concern:

Be it known that I, JAK ESENKO, a citizen of Austria-Hungary, residing at Mill Creek, in the Province of British Columbia, in the Dominion of Canada, have invented 5 certain new and useful Improvements in Expansible Shafts, of which the following is a specification.

This invention relates to improvements 10 in expansible shafts and more particularly to a shaft structure which is adapted when in expanded position to receive a web or continuous sheet of paper which may be wound thereupon to form a roll which roll 15 may be readily removed from said shaft when in contracted position.

My invention consists of a slotted cylinder secured in rotary bearings and provided with longitudinally extending springs which 20 lie in the slotted portions of said cylinder and obtain a bearing upon a central core or cam shaft which is carried by said cylinder and which while in normal position serves to keep the springs partially projected beyond 25 the periphery of the cylinder to form a bearing surface for the web and which core is capable of partial removal from said cylinder to permit the withdrawal of the springs into the cylinder to release the roll 30 when the same is formed by the web or continuous sheet of paper.

The invention consists in the combination and arrangement of parts to be hereinafter fully described in the following specification, 35 pointed out in the appended claims and illustrated in the accompanying drawings which form a part of said specification and in which—

Figure 1 is a longitudinal sectional view 40 of a portion of the mechanism showing the core in released position. Fig. 2 is a similar view showing the core in secured position. Fig. 3 is an end view of Fig. 2 and is taken on line 3—3 of that figure. Fig. 4 is a longitudinal sectional view of a portion of the mechanism showing the end opposite to that shown in Fig. 1 and the core in released position. Fig. 5 is a similar view showing 45 the core in secured position. Fig. 6 is a section taken on line 6—6 of Fig. 4. Fig. 7 is a cross section taken on line 7—7 of Fig. 4. Fig. 8 is a cross section taken on line 8—8 of Fig. 10. Fig. 9 is a similar view taken on line 9—9 of Fig. 2. Fig. 10 is a 50 perspective view of the cylinder. Fig. 11 is a similar view of one of the springs that

form a bearing surface for the web while the roll is being formed. Fig. 12 is a front view of the mechanism showing its application to a printing press or paper table. Fig. 60 13 is a plan view of Fig. 12 showing the roll ready for removal.

Like reference characters indicate corresponding parts throughout the several views.

The reference character 1 designates part 65 of the frame of a printing press or paper table provided with a bearing 2 having a removable top plate 3; and also a bracket 4 upon which a swivel bearing 5 is carried that supports a shaft 6 that extends through 70 and is also capable of obtaining partial support in a guide bracket 7 terminally secured to the table 1. The shaft 6 at one end is reduced in diameter and squared as at 8 to permit its releasable engagement 75 with a slideable coupling 9 by which it is operatively connected to the drive shaft 10 which shaft is provided with the expansion spring 11 to normally retain said coupling in operative relation. The shaft 6 aforesaid 80 is formed integral with an annular cap 12 which is threaded for engagement with the threaded exterior end of the cylinder 13 which is formed with the longitudinally extending slots 14 adapted to receive the 85 spring bars 15 which are formed with integral ribs 16 and with terminal feet 18 adapted to extend into the ends of the said cylinder as shown in Figs. 4 and 5 to prevent the separation of said members by gravity. 90

Within the cylinder a core or cam shaft 19 is arranged, the bulged portions of which are adapted to serve as bearings for the integral ribs 16 of the spring bars 15 when said shaft 19 is in normal position or when 95 completely telescoped within the cylinder. The said shaft 19 at one end is formed with a bore 20 adapted to receive the integral guide tongue 21 of the cap 12; the opposite end of said shaft being reduced as at 22 and projected beyond the end of the cylinder and into a coupling 23 which is formed with an interior annular shoulder 24 which serves as an abutment for the annular shoulder 25 of the cam shaft, formed by the junction of the reduced portion and the main portion of the shaft, when said shaft is in released or projected position with relation to the cylinder. The said coupling 23, further, is formed with an exterior annular shoulder 26 which abuts the end of the cylinder 13 which member is threaded for en- 100 105 110

gagement with said coupling. The reduced termination 22 of the cam shaft is formed with a threaded bore to permit its engagement with the threaded lug 27 of a socket 28 whereby said socket is supported and which socket normally abuts the free end of the coupling 23. An expansion spring 29 disposed about the reduced end of the cam shaft abuts the shoulder 24 of the coupling 23 and the socket 28.

Within the socket 28 a ball 30 is carried and retained in operative position by means of the apertured screw cap 31 applied to said socket, the ball partially projecting through the apertured portion of said cap to normally obtain a bearing upon an angular bracket 32 terminally secured to the table 1. Rotation of the drive shaft 10 will, through the medium of the coupling 9, rotate the shaft 6 which will rotate the cylinder and the complete shaft structure in its bearings, the ball 30 rotating against the bracket 32.

The web of paper to be wound is started about the spring bars 15 while they are in the position illustrated in Figs. 2 and 5 and rotation of the structure will wind the web thereupon and form a roll. To remove the roll the top plate 3 of bearing 2 is removed and the shaft structure gently swung upon its swivel support 5.

As the cap 31 moves out of the plane of the bracket 32 the ball 30 is released from engagement with that bracket and the spring 29 forces the socket 28 away from the coupling 23 and withdraws the cam shaft partially from the cylinder until the shoulder 25 of that shaft meets the shoulder 24 of the coupling. The bulged portions of the cam shaft are now disengaged from the ribs 16 of the spring bars which bars then assume the position illustrated in Figs. 1 and 4 or telescope into the cylinder, until the feet 18 obtain a bearing upon the cam shaft, when the roll may be readily removed in any approved manner.

What is claimed is:—

1. An expansible shaft structure comprising a supporting table provided with a bracket, a longitudinally slotted cylinder, a swivel bearing operatively associated with said cylinder, a rotary partitioned coupling terminally engaging said cylinder, a cam shaft arranged in said cylinder and rotary coupling and capable of longitudinal movement with respect to said members, spring bars movably arranged in the slotted portions of said cylinder and formed with integral ribs having a bearing upon the said cam shaft through the longitudinal movement of which latter member said spring bars are actuated, a socket terminally carried by said cam shaft, a ball retained in said socket and normally having a bearing upon the aforesaid bracket and an expansion

spring arranged about said cam shaft within said rotary coupling and abutting the partition in said member and the said socket whereby a longitudinal movement is imparted to said cam shaft as said cylinder is swung from the said swivel bearing. 70

2. An expansible shaft structure comprising a supporting table provided with a bracket, a longitudinally slotted cylinder, a swivel bearing operatively associated with said cylinder, a rotary partitioned coupling terminally engaging said cylinder, a cam shaft arranged within said cylinder and rotary coupling and capable of longitudinal movement with relation thereto, spring bars arranged in the slotted portions of said cylinder and formed with integral ribs having a bearing upon the said cam shaft through the longitudinal movement of which a transverse movement is imparted to said spring bars, a socket terminally carried by said cam shaft, a ball retained in said socket and normally having a bearing upon the aforesaid bracket and an expansion spring arranged about a portion of said cam shaft within said rotary coupling and abutting the partition in said member and the said socket whereby movement is imparted to said cam shaft when said cylinder is swung from its swivel bearing. 80

3. An expansible shaft structure comprising a supporting table provided with a bracket, a longitudinally slotted cylinder, a rotary shaft formed with an integral annular cap secured to said cylinder, a swivel bearing for said rotary shaft, a rotary partitioned coupling terminally engaging said cylinder, a cam shaft arranged within said cylinder and rotary coupling and capable of longitudinal movement with relation thereto, spring bars arranged in the slotted portions of said cylinder and formed with integral ribs having a bearing upon the said cam shaft through the longitudinal movement of which a transverse movement is imparted to said spring bars, a socket terminally carried by said cam shaft, a ball retained in said socket and normally having a bearing upon the aforesaid bracket and expansion means within said coupling and associated with said socket and cam shaft for imparting a longitudinal movement to the latter member as said rotary shaft is swung in its swivel bearing. 100

4. An expansible shaft structure comprising a supporting table, a swivel bearing carried by said table, a shaft supported in said swivel bearing, a guide bracket carried by said table and in engagement with said shaft, a longitudinally slotted cylinder, a cap formed integral with the said shaft and engaging said cylinder, a guide tongue formed integral with said cap and projected into said cylinder, a rotary partitioned coupling terminally engaging said cylinder, a 110

cam shaft arranged in said cylinder and rotary coupling and formed with a bore in one end to receive the said tongue and capable of longitudinal movement with respect to the said members, spring bars movably arranged in the slotted portions of said cylinder and formed with integral ribs having a bearing upon the said cam shaft through the longitudinal movement of which latter member said spring bars are actuated, a socket terminally carried by said cam shaft, a ball retained in said socket, an expansion spring arranged about said cam shaft within said rotary coupling and abutting the partition in said member and the said socket whereby longitudinal movement is imparted to said cam shaft as said cylinder is swung together with the first named shaft in the said swivel bearing and means carried by said table and normally in frictional engagement with the said ball whereby longitudinal movement of the same and its connections is normally obviated.

5. An expansible shaft structure comprising a supporting table, a swivel bearing carried by said table, a slotted cylinder operatively associated with said swivel bearing, rotary connection for one end of said cylinder, a support carried by said table for said rotary connection and capable of disengagement therefrom, a cam shaft arranged in said cylinder and capable of longitudinal movement with relation thereto, means disposed in the slotted portions of said cylinder for frictional engagement with said cam

shaft and operable thereby to engage or disengage a roll of paper upon said cylinder and means carried by said table and normally disposed in the plane of rotation of said cam shaft whereby relative longitudinal movement of the same is normally obviated.

6. An expansible shaft structure comprising a supporting table, a slotted cylinder, rotary connection for one end of said cylinder, a support for said rotary connection and capable of disengagement therefrom, a cam shaft arranged in said cylinder and capable of longitudinal movement with relation thereto, means disposed in the slotted portions of said cylinder in frictional engagement with the said cam shaft and operable thereby to engage or disengage a roll of paper upon said cylinder, means carried by said table and normally disposed in the plane of rotation of said cam shaft whereby relative longitudinal movement thereof is obviated and a swivel bearing carried by said table and operatively associated with said cylinder whereby the same may be swung out of association with the last named means to permit longitudinal movement of the said cam shaft.

In testimony that I claim the foregoing as my own I have hereto affixed my signature in the presence of two subscribing witnesses.

JAK ESENKO.
